[57] CLAIM

The ornamental design for a framework for wheelchair, as shown and described.

DESCRIPTION

FIG. 1 is a perspective view of a framework for a wheelchair showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof; and,

FIG. 8 is a left side elevational view of a framework for a wheelchair embodying my new design, it being understood that the broken lines are only for illustrative purposes and form no part of the claimed design.
